Inventor
Augustus Prentiss

UNITED STATES PATENT OFFICE.

AUGUSTUS PRENATT, OF BUFFALO, NEW YORK.

MACHINE FOR DRESSING HOOPS.

Specification of Letters Patent No. 22,581, dated January 11, 1859.

To all whom it may concern:

Be it known that I, AUGUSTUS PRENATT, of the city of Buffalo, in the county of Erie and State of New York, have invented certain new and useful Improvements in Hoop-Dressing Machines; and I do hereby declare that the following is a full and exact description thereof, reference being had to the accompanying drawings and the letters of reference marked thereon.

The nature of my invention relates, 1st, to the position of the cutters, in the cutter head, in reference to their axis of motion, and their consequent action upon the hoop to be dressed; which position may be defined as follows, viz: Placing the cutters in the cutter head, in such position that the plane of their cutting edge will cross their axis of motion at an angle of forty five degrees, (or nearly so), and also stand inclined to the horizontal plane of their axis, at an angle of forty five degrees, (or nearly so); 2d, in the arrangement of a cutter in a vertically moving frame or gate for the purpose of dressing the edge of the hoop, and for giving the hoop any required width.

Figure I, is a top plan view of my machine. Fig. II, is a side elevation of the same. Fig. III, is an elevation of the vertically moving gate, which supports the cutter, for dressing the edge of the hoop.

Letters of like name and kind refer to like parts in each of the figures.

A, plate, which supports the upper portions of the mechanism. This plate is bolted to the main frame; B, cutter head.

C, cutter. This is bolted or made fast to the cutter head and is so placed therein, as that the plane of its cutting edge will cross its axis of motion at an angle of forty five degrees, and its plane also inclines toward its axis of motion at an angle of forty five degrees or nearly so. This position of the cutter in connection with the direction of the hoop as it is fed to the cutters insures a uniform drawing cut through its whole line of operation. There are three cutters in the cutter head.

D, fence or guide. This is made fast to the plate (A). It serves the purpose of warding off the hoop from the cutter head and prevents the hoop from being crowded on to the cutters in consequence of knots or other irregularities, upon its outside. This

fence may also be made adjustable so as to 55 allow hoops to be dressed from crooked timber and of different thicknesses, as circumstances may require.

E, guide roller. This is covered with gutta percha or india rubber, so that in case 60 there are knots or other irregularities in the hoop to be dressed the gutta percha will yield to the knots and thus insure an even surface on the dressed side of the hoop. The fence (D) being fixed in its position it prevents the gage roller from crowding the hoop too much on to the cutter head, and hence the gutta percha must yield to the knots. By this arrangement a hoop may be dressed to a uniform thickness, notwithstanding the irregularities on its outside 70 surface.

F, vertically moving frame or gate, which supports the cutter for dressing the edge of the hoop; G, cutter.

H, adjustable roller which rolls on the undressed edge of the hoop, as the hoop passes through the machine. If the hoop is crooked on its upper edge, it will cause the gate to rise and fall in conformity therewith, and the cutter being fixed in the gate, will at all times be equidistant from the roller, the hoop will be dressed to an equal width; I, spring guide; J, J, feed rollers; K, spring roller under which the hoop passes before it 85 is taken by the feed rollers; L, L, feed rollers; P, Q, R, band and pulley for driving the cutters; S, T, U, band and pulley for driving cutter (G) in the vertically moving gate; W, main shaft on which there is a 90 worm, which meshes in with worm wheels V and X, and through the series of gear wheels drives the feed rollers as represented in the drawing; Z, lower plate which is bolted to the lower timbers of the main frame. This plate supports the lower portions of the mechanism; X Y, main frame of the machine. The lower ends of the shafts (1, 2,) stand in oscillating boxes.

Power is applied to the machine in a common manner.

What I claim as my invention and desire to secure by letters patent, is—

1. Placing the cutters (C) in the cutter head (B) in such position that the plane of their cutting edge will cross their axis of motion at an angle of forty five degrees (or nearly so), and also stand inclined to the

horizontal plane of their axis at an angle of forty five degrees (or nearly so) substantially as set forth.

2. I claim the arrangement of the cutter 5 (G) in the vertically moving gate (F) (including the adjustable roller H,) for the purpose of dressing the edge of the hoop,

and for giving the hoop any required width, as herein described.

AUGUSTUS PRENATT.
